CONNECTION ACTUATED RECEPTACLE
SWITCH

Jerome J. Sperrazza, Buffalo, N. Y.

Application January 31, 1947, Serial No. 725,455

2 Claims. (Cl. 200—51.09)

1

This invention relates to improvements in electrical connection receptacles and more particularly to electrical wall outlets or receptacles such as those used in buildings to receive the plugs of lighting and appliance fixtures.

The primary object of the present invention is to provide an electrical connection receptacle wherein the safety factor is greatly increased by so constructing the receptacle as to eliminate the hazard of receiving a shock or burn by inserting a foreign object into one of the openings in the receptacle normally receiving a prong of the usual electrical plug.

This increased safety factor is attained by so constructing the receptacle that the circuit through its terminals can be closed only by inserting suitably shaped projections, such as the prongs of an outlet plug, in both of the two openings of the receptacle simultaneously. This may be accomplished by having the contacts in the openings of the receptacle normally dead and so arranging the parts that each contact may be made alive only by inserting a suitable projection or prong in another or the other opening of the receptacle. With the receptacle so constructed, if one were to insert a pin or wire in one opening of the receptacle and manipulate it so as to move a part or parts located in the opening which may be moved, even so he would not receive a shock as a result of closing the circuit because the movement effected by the wire or pin would only close the electrical connection to the contact in the other opening of the receptacle; it would not close the circuit, and, in particular, would not close the electrical connection to the contact in the opening in which the pin or wire was inserted, with resultant shock to the operator of the pin or wire. Thus, the circuit can be closed at the receptacle only by inserting elements into both of the openings of the receptacle simultaneously and thus manipulating the movable parts located in the two openings simultaneously; in a practical sense, this permits of closing the circuit at the receptacle only by inserting the two prongs of the plug into the two openings of the receptacle.

A receptacle so constructed as to embody the invention may take many different structural forms, but stated generally, each such form will include movable parts associated with the openings of the receptacle so as to be moved by the entrance of the prongs into the receptacle, and means whereby the movement of the part associated with one of the openings closes a break in a path for electric current to a conducting

2

member located in the other opening of the receptacle, thereby supplying current to a prong entered therein. In this application, I illustrate and describe in detail one structural form in which the invention may be utilized; other structural forms having the same distinctive features and therefore also embodying the invention are illustrated and described in an application for U. S. patent filed by me on April 13, 1948, and serially numbered 20,632, and in an application for U. S. patent filed by Harvey Hubbell on April 8, 1948, and serially numbered 19,682.

In the accompanying drawings forming a part of this application:

15 Fig. 1 is a top plan view of a twin type receptacle embodying the features of the present invention and showing the receptacle mounted in a conventional electrical wiring box and provided with a conventional cover plate.

20 Fig. 2 is a side elevational view of the devices shown in Fig. 1.

Fig. 3 is a vertical central sectional view through the wiring box and cover plate, with the receptacle embodying the present invention shown in elevation.

Fig. 4 is a horizontal sectional view taken on line 4—4 Fig. 3.

Fig. 5 is a horizontal sectional view through the receptacle, looking down on the operative parts thereof.

30 Fig. 6 is an enlarged fragmentary sectional view similar to that of Fig. 5, showing the disposition of the operative parts of one of the outlets of the receptacle with the prongs of a plug inserted therein.

Fig. 7 is a vertical sectional view taken on line 7—7, Fig. 6.

Fig. 8 is a vertical transverse sectional view taken on line 8—8, Fig. 6.

40 Fig. 9 is a fragmentary vertical sectional view taken on line 9—9, Fig. 6.

Fig. 10 is a fragmentary vertical transverse sectional view taken on line 10—10, Fig. 6.

45 Fig. 11 is a perspective view of one of the cam members adapted to be engaged by a prong of a plug.

Referring to Figs. 1 to 4 of the drawings, the improved receptacle of the present invention is shown mounted on the usual sheet metal electrical wiring box 10, open on one side and provided with the usual ears 11 on opposite ends thereof for attachment to any suitable supporting surface such as a wall, floor or the like, according to present practice. The receptacle illustrated is of the duplex or twin outlet type having two pairs

of outlet openings, although it will be understood that any number of outlets can be provided. This receptacle comprises a body 12 formed of upper and lower sections 13 and 14 connected together to form a unitary structure. The body 12 may be of any suitable rigid electrical non-conductive or insulating material such as the plastics now commonly used for the bodies of conventional receptacles. While the body sections 13 and 14 can be built up in any desired manner and suitably connected together, they are preferably cast or molded to shape.

The upper section 13 is similar to exterior shape to that of conventional receptacles, since it is provided with a pair of integral bosses 15 and 15' extending outwardly. A conventional cover plate 16 having the usual openings to receive the bosses is mounted on the receptacle and secured to the body section 13 by a screw 18. The bosses 15 and 15' are provided respectively with a pair of similar spaced plug-prong-receiving outlet openings 19, 19' and 20, 20', which extend completely therethrough and lead respectively to the outer surface of the bosses. Each outlet opening is rectangular in cross-section so as to receive the similarly shaped prongs 21 and 21' of a conventional type electrical plug 22 shown inserted in the openings 19 and 19' in Figs 5 to 8.

Conventional type openings are advantageously used because most conventional plugs have prongs which are substantially rectangular in cross-section, either in the form of a solid bar as indicated by prong 21, or in the form of a reversely bent contact element (not shown). Special plugs will therefore not be required. However, the outlet openings, if desired, may be of any other shape in cross-section to receive the prongs of plugs having similar cross-sectional shapes.

Electrical contact means of similar structure are associated with all outlet openings, comprising electrical contact elements 23 and 23' for the outlet openings 19 and 19', respectively, and elements 24 and 24' for the outlet openings 20 and 20', as shown in Figs. 5 to 7. The element 23, which is illustrative of all, is made of electrically conductive flat strip material and includes a stationary contact part 25 in the opening 19, an offset movable contact part or spring finger 26 extending generally toward the outlet opening 19', and an intermediate part 27 connecting the part 26 at one end with the inner end of the stationary contact part 25. The stationary contact part 25 of element 23 is arranged in the opening 19 against the outer side thereof so that its inner flat side is adapted to have a wiping contact with the prong 21 of the plug 22. The movable contact finger 26 and the curved intermediate part 27 are accommodated in a recess 29 provided in the body section 13, this recess extending upwardly from the bottom flat face of the body section, as shown in Fig. 7. The recess 29 is of greater width than the contact finger 26 and intermediate part 27, so as to permit the contact finger 26 to move for a purpose hereinafter described. In this connection the contact element 23 is so bent that the contact finger 26 is springy and is normally biased toward the adjacent outlet opening 19' or against the inner wall of the recess 29, as shown in Fig. 5. The structure and arrangement of the other contact elements are the same as the element 23.

The recess 29 and the others like it in the upper body section 13 are closed by the lower body

section 14, which is shown in the form of a flat plate fitting against the bottom face of the upper body section 13 and secured thereto by screws 30, Figs. 4 and 8. A recess 31 is provided in the lower body section 14 below each outlet opening to accommodate the ends of the plug prongs, as shown in Figs. 7 and 8.

Electric current is supplied to the four contact elements of the receptacle by current supply bars 32 and 32', each of which is bent near its ends, as illustrated by the bar 32, to provide contacts 33 and 33', respectively engageable by the free ends of the movable contact fingers of the contact elements 23 and 24. The members 32 and 32' are mounted in the same manner, for example the bar member 32 is arranged in a recess 34 in section 13, which at one end communicates with the recess 29 and at the other with a similar recess for contact 24. The bar 32 is prevented from moving or shifting in the recess 34 by projections 35 on its upper edge fitting into recesses 36 provided in the body section 13, as shown in Fig. 9. The bent end 33 of the bar 32 extends into the recess 29 in the upper body section 13 while the bent end 33' extends into a similar recess for the element 24. The current supply member 32' has bent contact ends 38 and 38'. The contact fingers, such as 26, are normally out of contact with the current supply members as shown in Fig. 5.

The current supply bars 32 and 32' are each connected to a terminal plate 39 by an integral connector 40, depending therefrom. The terminal plate 39 extends into a cut-out 41 in the lower body section 14, as shown in Figs. 9 and 10. Electrical energy is supplied respectively to bars 32 and 32' by lead wires 42 and 42' connected to the respective plates 39 by terminal screws 43, which extend through holes provided in the terminal plates 39 and which screw into threaded holes provided in the lower body section 14, as shown in Figs. 3, 4, 9 and 10. The opposite ends of the lead wires are suitably connected to a main supply line 44 (Figs. 2 and 3).

The means for moving the free ends of the movable contact fingers into contact with their current supply members, such as the movement of the finger 26 into engagement with the contact end 33 of the supply member 32, comprise cam members 45 of non-conductive material having the structure of the cam member 45 arranged between the movable contact finger 26 and the outlet opening 19', as shown in Figs. 5, 6, 7 and 11. The cam member 45 is shown as being in the form of a block set in a slot or guideway 46, provided in the bottom of the upper body section 13, and arranged for sliding movement toward and from the opening 19' along with the movable contact finger 26, in a direction extending generally transversely to the finger. The slot or guideway 46 in which the cam member 45 is slidingly arranged opens at its outer end into the recess 29 so that the cam member can project from the slot 46 into the recess 29 to move the finger 26 into engagement with the current supply contact 33, as shown in Fig. 6. At its opposite end, the slot or guideway 46 is enclosed with an end wall 48 which is in substantially vertical alignment with the adjacent edge wall of the opening 19' so as to place the slot 46 in communication therewith.

The cam member 45, on the side facing the opening 19', is provided with a cam projection 49 having a cam face or surface 50 facing the opening 19', as best shown in Figs. 6, 7 and 11. The

part 49, as shown in Fig. 5, normally projects into the opening 19 through the opening provided in the inner wall 48 of the slot or guideway 46, movement of the cam projection 49 into the opening 19 being limited by the end wall 48 engaging the opposing end face of the cam member 45. The cam member 45 is urged to this normal position by the spring action of the movable contact finger 26 which engages its outer end face.

The cam member 45 at the opening 19 is actuated by inserting a suitable object such as the prong 21' of the plug 22 into the opening 19' which will displace the cam member from the inoperative position shown in Fig. 5 to the operative position thereof shown in Fig. 6. More particularly, as the prong 21' moves into the opening 19', the outer edge of the inner end or corner of the prong engages the cam face 50, and as the prong 21' is pushed farther into the opening, the cam member 45 slides in its slot or guideway 46 until the cam projection 49 is moved out of the opening 19'. This movement of the cam member 45 is against the urging or resistance of the spring finger 26, and the free end of this contact finger 26 is moved against the opposing side of the current supply contact 33, thereby forming a connection through the element 23 to the plug prong 21 in opening 19.

The cam member 45 is made of non-conductive material, and therefore no current will be conducted by it from the contact finger 26 to the prong 21'. Furthermore, when this prong 21' is removed from the outlet opening 19' the cam member 45 will be moved by the spring contact finger 26, as it disengages the contact 33, from the operative position shown in Fig. 6 to the inoperative position shown in Fig. 5, thereby breaking the circuit to the element 23 and the plug prong 21 in the opening 19.

The contact part 25 and curved intermediate part 27 of the element 23 are held against displacement or shifting in the recess 29 and opening 18 by arranging the contact part 25 against the outer vertical side wall of the opening 19, and by arranging the inner side of the salient part of the curved intermediate part 27 on an abutment 51, as shown in Figs. 5 and 6. The abutment 51 forms the inner wall of that part of the recess 29 which accommodates the intermediate part 27. The contact element 23 is therefore constrained against being displaced except for movement of its movable spring contact finger 26 thereof, the abutment 51 serving as a fulcrum for such movement of the contact finger. The contact elements 23', 24 and 24' have the same structure as the element 23 and are arranged in the body section 13 in the same manner, the movable contact finger of the element 23' being operated by a cam member 45', that of element 24 by a cam member 45², and the spring finger of element 24' by a cam member 45³. These fingers respectively engage current supply contacts 38', 33' and 38, and in general it will be seen that the operating means associated with each of the outlet openings are alike, including the cam members.

In the operation of the receptacle, as shown in Figs. 6 and 8, the insertion of the prongs 21 and 21' of the plug 22 in the outlet openings 19 and 19' effects a wiping contact with the contact elements 23 and 23' before the cam members 45 and 45' move the contact fingers of these elements into contact with the live current supply contacts 33 and 33'. By this means and arrangement, arcing in the outlet openings 19 and 19' is prevented. It will also be noted that the prongs 21

and 21' of the plug 22 must be inserted in the outlet openings 19 and 19' substantially their full length before the contact fingers of elements 23 and 23' are caused to engage the live ends 33 and 33'. Hence the person inserting the plug 22 is protected against being burned or shocked in case his fingers deliberately or inadvertently touch the prongs of the plug before they have been pushed all the way into the outlet openings.

Furthermore, as illustrated in Fig. 7, a person is not endangered if he inserts a foreign object such as a bobby pin, even though made of conductive material, into one of the outlet openings. Normally the contact parts arranged in the outlet openings, such as the part 25, are dead, but if the foreign object inserted into one of these outlet openings should move the cam member, this would merely connect the contact element in the opposite outlet opening to the current supply. The opening in which the foreign object is inserted, however, remains dead, and therefore a very desirable safety feature is provided. In order to make both openings of a pair alive, a suitable object must be inserted into each opening in such a way as to displace the cam member associated therewith and cause the same to move the corresponding contact finger into engagement with the live current supply contact therefor. This action takes place when the prongs of the plug 22 are inserted in a pair of the holes or openings.

The receptacle embodying the present invention is suitably mounted on the electrical wiring box 10 so that its inner or bottom side, as viewed in Fig. 3, is spaced from the bottom of the box 10 to provide space for the lead wires 42 and 42'. This is in accordance with conventional electrical wiring practice. The body 12 of the receptacle is not as deep or thick as some conventional types of receptacles and therefore, if desired, can be mounted on a shallower wiring box 10 than presently being used for this type of receptacle and still provide the amount of space between the box and receptacle, to accommodate the wiring, as required by present building codes. In this connection, also if desired, the terminal plates 39 of the current supply members 32 and 32' can be provided with one or more additional terminal screws similar to the screws 43 for attachment of additional lead wires (not shown), such as for running lead wires to another receptacle at a remote point.

While the body 12 may be variously mounted on the electrical wiring box 10, it is shown as having molded therein a horizontal attaching plate 60 (Figs. 3 and 8) which extends completely through the body 12 and is formed at its ends to provide an attaching gear 61 on opposite ends of the body 12, as shown in Figs. 2, 3, 4 and 8. Each of these ears 61 is provided with an opening to receive an attaching screw 62 which screws into a threaded hole provided in a mounting ear 63 on the wiring box 10.

From the foregoing description it will be seen that the present invention provides a safe electrical connection receptacle in which the outlet openings are normally dead, and that one opening can only be made live by the insertion of a suitable object into another opening, thereby providing protection particularly against injury to children who are prone to insert foreign objects into such receptacles. The improved receptacle is adapted to receive conventional type plugs and therefore does not require a special plug; it can 75 replace conventional types of wall receptacles

since it is installed in the same manner; and it is simple, serviceable and inexpensive to manufacture.

I claim:

1. An electrical plug receptacle, comprising a body having two separable parts connected together, a pair of terminals arranged within said body and between said body parts and each adapted to be connected to a source of electrical energy, one of said body parts being provided with a pair of outlet openings arranged between said terminals, an electrical contact part arranged in each of said openings, a movable contact member for and connected to each of said contact parts and operatively arranged in opposing relation to one of said terminals and normally disconnected therefrom, and an actuating member of insulating material for and associated with each of said openings and arranged between opposed guide surfaces of said two body parts for rectilinear movement and so rectilinearly movable upon the insertion of an object in the corresponding opening to move the movable contact member for the other outlet opening into contact with its terminal.

2. An electrical plug receptacle, comprising a body having two separable parts connected together, a pair of spaced generally parallel terminal bars arranged within said body between said body parts and each having a terminal intermediate its ends adapted to be connected to a source of electrical energy, one of said body parts being provided with a pair of outlet openings arranged

between each of the corresponding ends of said terminal bars, an electrical contact part arranged in each of said openings, a movable contact member for and connected to each of said contact parts and operatively arranged in opposing relation to one of the adjacent ends of said terminal bars and normally disconnected therefrom, and an actuating member of insulating material for and associated with each of said openings and arranged between opposed guide surfaces of said two body parts for rectilinear movement and so rectilinearly movable upon the insertion of an object in the corresponding opening to move the movable contact member for a different outlet opening into contact with its terminal bar.
